UNITED STATES PATENT OFFICE.

JOSEPH E. BAINES, OF PITTSBURGH, AND JACOB P. BOSLE, OF MOUNT OLIVER, PENNSYLVANIA, ASSIGNEES TO NATIONAL TUBE COMPANY, OF PITTSBURGH, PENNSYLVANIA, A CORPORATION OF NEW JERSEY.

CHUCK-OPERATING MECHANISM.

Application filed September 23, 1926. Serial No. 137,280.

This invention relates to chucks and more particularly to chucks such as used on pipe-working machines and the like, and has for its object the provision of a device of this character which while in motion may be caused to grip or release the work without the necessity of stopping the machine to which the chuck is applied.

Another object is to provide a means, controllable from a point remote from the chuck, for operating the chuck to cause it to grip and release the work.

A further object is to provide a chuck having the novel combination, design and construction of parts hereinafter described and illustrated in the accompanying drawings.

In the drawings:

Figure 1 is a partial side elevation of a pipe-working machine embodying this invention.

Figure 2 is a rear end elevation thereof.

Figure 3 is a plan of the chuck with the cover or cap and keeper-ring removed.

Figure 4 is a sectional view on the line IV—IV of Figure 3.

Figure 5 is a horizontal sectional view through the tripping mechanism.

Figure 6 is a sectional view on the line VI—VI of Figure 5.

Figure 7 is a sectional view of a modified chuck construction, with the cover or cap and keeper ring removed.

Figure 8 is a sectional view on the line VIII—VIII of Figure 7.

Referring more particularly to the drawings, the numeral 2 designates the base of the machine as a whole, on which is supported a housing 3. A barrel 4 is journaled in the housing 3 and is provided intermediate its ends with an external worm-wheel 5 which is in mesh with a worm 6 on a shaft 7 journaled in the housing 3. A motor 8 is mounted on an adjustable motor base 9 on the top of the housing and is connected to the shaft 7 by a chain or belt 10 trained over sprockets 11 and 12 on the motor-armature shaft 13 and the drive-shaft 7, respectively.

The above described machine is of common and well-known design and, therefore, will not be further described.

In order to grip a pipe in the barrel 4

and cause it to rotate therewith the novel chuck, designated generally by the letter A, 55 is secured to the rear end of the barrel 4.

The chuck A comprises a main cylindrical or ring-like body portion or housing 15 which is secured by bolts 16 to the flange 17 on the rear end of the barrel 4.

A cam-ring 18 is mounted within the body portion 15 and is keyed thereto by a key 19 so as to prevent rotation of the ring 18 relative to the body 15. The inner periphery or face of the cam-ring 18 is provided with a plurality of cam-plates 20 of hardened steel.

A roller retaining ring 21 is mounted within the cam-ring 18 and has an outwardly extending flange portion 22 overlying the rear side face of the cam-ring 18. An actuator-ring 23 is mounted around a projecting ring portion 24 of the body 15 and has an inwardly extending flange portion 25 which is keyed at 26 to the flange 22 75 of the roller retaining ring 21.

The roller retaining ring 21 is provided with a plurality of outwardly flaring or tapered slots or pockets 27 in which are mounted the pipe gripping rollers 28 which have a slightly greater diameter than the inner ends of the slots so as to permit the rollers to project through said slots to engage the pipe or work-piece and yet prevent their moving entirely out of the slots.

The cam-plates 20 are adapted to form bearing surfaces for the rollers 28 and to force the rollers into engagement with the pipe or work-piece when the cam-ring is moved clockwise relative to the roller retaining ring 21.

The outer periphery of the actuator-ring 23 is provided with teeth 30 adapted to be in mesh with pinions 31 and 32 journaled on shafts or axles 33 and 34, respectively, mounted in the body or housing 15.

The housing 15 is recessed at diametrically opposite points as at 35 and 36 to provide a space to receive the pinions 31 and 32 and to also receive rack-blocks or segments 37 and 38.

The rack-block 37 is slidably mounted in the recess 35 and has its rack or toothed face 39 in mesh with the pinion 31.

The rack-block 38 is slidably mounted in the recess 36 and has its rack or toothed face

40 in mesh with a pinion 41 journaled on an axle or shaft 42 and meshed with the pinion 32.

The blocks or segments 37 and 38 are recessed or slotted to receive stop-blocks 43 and 44, respectively, which are movable in the recesses and are held in normal position by compression springs 45 and 46, respectively. The springs 45 and 46 provide an elastic resistance to the movement of the blocks 43 and 44 in their respective recesses.

The blocks 43 and 44 are adapted to be engaged by tripping-bars or stops to be described.

15 Cam-shoes 48 and 49 are mounted on the periphery of the chuck adjacent the blocks 43 and 44 so that the tripping-bars will be automatically disengaged after a predetermined travel of the chuck sufficient to dis- 20 engage the rollers 28 from the work.

The actuating ring 23, axles or shafts 33, 34 and 42, pinions 31, 32, and 41, sliding-rack blocks or segments 37 and 38, and blocks 43 and 44, are held in place and 25 in proper relation to each other by a cover-plate or cap 50 which is bolted to the housing 15.

The cam-ring 18 and roller retaining ring 21 are held in place by a keeper-ring 51 extending inwardly from and bolted to the cover-plate 50.

In order to yieldably hold the chuck in its open position a pin 52 is mounted in a recess 53 in the housing 15 and pressed outwardly 35 toward the cover-plate 50 by a spring 53, so as to enter a hole 54 in the cover-plate when the chuck is open.

The base 2 of the machine is extended rearwardly to form a bracket 55 on which is mounted a trip housing or body 56 which may be secured thereto in any manner. Trips 57 and 58 are slidably mounted in openings formed in the body 56 and are adapted to be projected into the path of the blocks 43 and 44 and double ended cam-shoes 48 and 49. The trips 57 and 58 are of like formation and are disposed side by side. The trip 57 is adapted to be projected into the path of the cam-shoe 48 and the block 43. The trip 58 is adapted to be projected into the path of cam-shoe 49 and the block 44. The trips 57 and 58 are normally acted upon by means of expansible helical springs 59 which abut at their upper ends against the lower ends of the trips and engage a bracket 60 at their lower ends, such bracket being secured at its upper end to the body 56. Pins 61 pass through the springs 33 and engage the respective trips 57 and 58. A pair of nuts 62 are mounted upon the lower ends of the pins 61 and permit of adjusting the trips. To deaden the noise incident to engagement of the nuts 62 with the bracket 60, a plurality of washers 63 are mounted upon the pins 61, the outer ones of

the washers being composed of leather or other sound deadening material.

The trips 57 and 58 are held in lowered position against the tension of the springs 59 by means of lock-bolts 65 which are slidably mounted in the body 56 to slide in a direction at right angles to the movements of the trips 57 and 58. Each of the lock-bolts 65 is formed with a depending portion 66 at its outer end and this depending portion is utilized to receive a pin 67 and to form a shoulder or abutment to be engaged by means of a cam 68.

The pins 67 extend through openings formed in a cap-plate 69 secured to the body 56. Expansible helical springs 70 are mounted upon the pins 67 and are confined between the cap-plate 69 and the outer ends of the lock-bolts 65 and normally tend to press the bolts inward into engagement with the trips. Each of the trips is formed in the side with a notch 71 to receive the inner end of the cooperating lock-bolt 65 whereby the trip is held depressed against the tension of the spring 59.

In order to operate the lock-bolts 65 to effect the release of the trips, a spindle 72 is mounted in the body 56 and is provided at its lower end with the cam or cross-head 68 and at its upper end with the arm 74. The ends of cross-head or cam 68 are adapted to engage the depending portions 66 of the lock-bolts. Rotation of the spindle 72 in one direction brings one end of the cam or cross-head 68 into engagement with the depending portion of one of the lock-bolts, thereby releasing one of the trips, while rotation of the spindle in the reverse direction will bring the other end of the cam or cross-head 68 into engagement with the depending portion of the other lock-bolt.

For convenience of operating the spindle 72 a link 75 connects the outer end of the arm 74 with a lever 76 conveniently disposed to be operated by the operator at a point 110 distant from the chuck.

In operation, the pipe or other article is mounted in the barrel 4 and chuck A, and the machine is caused to operate to rotate the barrel 4 in a clockwise direction. The operator will then operate the lever 76 to release the trip 58 which is projected upwardly into the path of the block 44. As soon as the block 44 comes in contact with the trip 58, it will stop and the segment 38 will be retarded. As the pinions 41 and 32 are carried forward they will rotate on their axles, and the actuating ring 23 and roller retaining ring 21 will remain stationary, while the cam-ring 18 will revolve with the chuck-body 15 and force the rollers 28 into gripping engagement with the work-piece.

It will be noted that the block 44 will be held stationary only until the trip 58 is depressed by the cam-shoe 49. Should the

rollers 28 begin to grip the pipe or work-piece before the block 44 is released, the spring 46 will be compressed and avoid excessive strain on the parts.

- 5 In order to release or open the chuck, the operator will move the lever 76 to release the trip 57 which will be projected upwardly into the path of the block 43. As soon as the block 43 engages the trip 57 it will 10 stop and the segment 37 will be retarded. As the pinion 31 is carried forward it will rotate on its axle and the actuating ring 23 and roller retaining ring 21 will rotate with reference to the cam-ring 18 so as to release 15 the rollers 28.

In Figures 7 and 8 we have shown a plan and section of a slightly modified form of chuck in which lever mechanism is substituted for the rack and pinion operating 20 mechanism above described.

A lever 78 has an articulated connection at one end with the block 43 and is pivoted at its other end to a shaft 79 mounted in the chuck housing 15. A second lever 80 25 has an articulated connection at one end with the actuating ring 23 and is pivoted intermediate its ends to a shaft 81 and has its free end pivotally connected to a connecting rod 82, the other end of which is 30 pivotally connected to the lever 78 intermediate its ends. The connecting rod 82 is composed of two telescoping parts normally held extended by a coiled spring 83. Torsion springs 84 and 85 are connected to 35 each of the levers 78 and 80 to urge them into normal position.

When the trip 57 is released to engage the block 43, the levers 78 and 80 and connecting rod will cooperate to rotate the actuating ring 23, and roller retaining ring 21 will rotate relative to the cam-ring 18 so as to release the rollers 28.

A lever 85 has an articulated connection at one end with the block 44 and is pivoted at its other end to a shaft 86 mounted in the chuck housing 15. A second lever 87 has an articulated connection at one end with the actuating ring 23 and is pivoted at its other end to a shaft 88 mounted in the 50 chuck housing 15. A connecting rod 89 is pivotally connected at its opposite ends to points intermediate the ends of the levers 85 and 87. The connecting rod 89 is composed of two telescoping parts normally held extended by a coiled spring 90. Torsion springs 91 and 92 are connected to 55 each of the levers 85 and 87 to urge them into normal position.

When the trip 58 is released to engage 60 the block 44, the levers 85 and 87 and connecting rod 89 will cooperate to hold the actuating ring 23 and roller retaining ring 21 stationary, while the cam-ring 18 will revolve with the chuck-body 15 and force the rollers 28 into engagement with the work-piece.

While we have shown and described certain specific embodiments of our invention, it will be understood that we do not wish to be limited thereto since various modifications may be made without departing 70 from the scope of our invention as defined in the appended claims.

We claim:

1. The combination with a pipe-working machine or the like having a positively rotated barrel, of a chuck comprising a main body portion secured to and adapted to rotate with said barrel, a cam-ring removably secured to and adapted to rotate with said body portion, a roller retaining ring 75 mounted within said cam-ring and adapted to move relative thereto, said roller retaining ring being provided with a plurality of transverse slots, a plurality of roller-jaw members mounted in said slots, cam-faces 80 on said cam-ring adapted to engage and control the movement of said jaws relative to the work, means for holding said roller-ring stationary while said cam-ring is rotated relative thereto thus causing said cam-faces to force said roller-jaws against the work, means for causing said roller-ring to move relative to said cam-ring in the direction of rotation of said cam-ring to thereby permit said roller-jaws to move 85 from the work, and selective means controllable from a point remote from said chuck for operating either of the above mentioned means.

2. The combination with a pipe-working machine or the like having a positively rotated barrel, of a chuck comprising a main body portion secured to and adapted to rotate with said barrel, a cam-ring removably secured to and adapted to rotate with said body portion, a roller retaining ring 90 mounted within said cam-ring and adapted to move relative thereto, said roller retaining ring being provided with a plurality of transverse slots, a plurality of roller-jaw members mounted in said slots, cam-faces 95 on said cam-ring adapted to engage and control the movement of said jaws relative to the work, a toothed ring mounted around said roller retaining ring and secured thereto, a pinion mounted on said body portion and in mesh with said toothed ring, a segmental rack mounted for sliding movement relative to said body portion, a second pinion mounted on said body portion 100 and in mesh with said rack and said first named pinion, said rack being adapted to be held stationary while said chuck body and pinions are moved relative thereto, whereby 105 said toothed ring and roller-jaw retaining ring are held stationary while said cam-ring is rotated relative thereto thus causing said cam-faces to force said roller-jaws against the work, a second segmental rack, a pinion 110 mounted on said body portion and in mesh 115 with said second rack, a pinion mounted on said body portion and in mesh with said second rack, a pinion mounted on said body portion and in mesh 120 with said second rack, a pinion mounted on said body portion and in mesh with said second rack, a pinion mounted on said body portion and in mesh 125 with said second rack, a pinion mounted on said body portion and in mesh with said second rack, a pinion mounted on said body portion and in mesh 130 with said second rack.

with said rack and said toothed ring, said last named rack being also adapted to be held stationary while said chuck body and last named pinion are moved relative thereto, whereby said toothed ring and roller-jaw retaining ring are caused to move relative to said cam-ring in the direction of rotation of said cam-ring to thereby move said cam-faces away from said roller-jaws and release the work.

3. The combination with a pipe-working machine or the like having a positively rotated barrel, of a chuck comprising a main body portion secured to and adapted to rotate with said barrel, a cam-ring removably secured to and adapted to rotate with said body portion, a roller retaining ring mounted within said cam-ring and adapted to move relative thereto, said roller retaining ring being provided with a plurality of transverse slots, a plurality of roller-jaw members mounted in said slots, cam-faces on said cam-ring adapted to engage and control the movement of said jaws relative to the work, a toothed ring mounted around said roller retaining ring and secured thereto, a pinion mounted on said body portion and in mesh with said toothed ring, a segmental rack mounted for sliding movement relative to said body portion, a second pinion mounted on said body portion and in mesh with said rack and said first named pinion, said rack being adapted to be held stationary while said chuck body and pinions are moved relative thereto, whereby said toothed ring and roller-jaw retaining ring are held stationary while said cam-ring is rotated relative thereto thus causing said cam-faces to force said roller jaws against the work, a second segmental rack, a pinion mounted on said body portion and in mesh with said rack and said toothed ring, said last named rack being also adapted to be held stationary while said chuck body and last named pinion are moved relative thereto, whereby said toothed ring and roller-jaw retaining ring are caused to move relative to said cam-ring in the direction of rotation of said cam-ring to thereby move said cam-faces away from said roller-jaws and release the work, and selective means controllable from a point remote from said chuck for holding either of said racks stationary.

40 35 40 45 50

4. The combination with a pipe-working machine or the like having a positively rotated barrel, of a chuck comprising a main body portion secured to and adapted to rotate with said barrel, a cam-ring removably secured to and adapted to rotate with said body portion, a roller retaining ring mounted within said cam-ring and adapted to move relative thereto, said roller retaining ring being provided with a plurality of transverse slots, a plurality of roller-jaw members mounted in said slots, cam-faces on

said cam-ring adapted to engage and control the movement of said jaws relative to the work, a toothed ring mounted around said roller retaining ring and secured thereto, a pinion mounted on said body portion and in mesh with said toothed ring, a segmental rack mounted for sliding movement relative to said body portion, a second pinion mounted on said body portion and in mesh with said rack and said first named pinion, said rack being adapted to be held stationary while said chuck body and pinions are moved relative thereto, whereby said toothed ring and roller-jaw retaining ring are held stationary while said cam-ring is rotated relative thereto thus causing said cam-faces to force said roller jaws against the work, a second segmental rack, a pinion mounted on said body portion and in mesh with said rack and said toothed ring, said last named rack being also adapted to be held stationary while said chuck body and last named pinion are moved relative thereto, whereby said toothed ring and roller-jaw retaining ring are caused to move relative to said cam-ring in the direction of rotation of said cam-ring to thereby move said cam-faces away from said roller-jaws and release the work, and selective means controllable from a point remote from said chuck for holding either of said racks stationary.

5. The combination with a pipe-working machine or the like having a positively rotated barrel, of a chuck comprising a main body portion secured to and adapted to rotate with said barrel, a cam-ring removably secured to and adapted to rotate with said body portion, a roller retaining ring mounted within said cam-ring and adapted to move relative thereto, said roller retaining ring being provided with a plurality of transverse slots, a plurality of roller-jaw members mounted in said slots, cam-faces on said cam-ring adapted to engage and control the movement of said jaws relative to the work, a toothed ring mounted around said roller retaining ring and secured thereto, a pinion mounted on said body portion and in mesh with said toothed ring, a segmental rack mounted for sliding movement relative to said body portion, a second pinion mounted on said body portion and in mesh with said rack and said first named pinion, means cooperating with said rack for holding said rack stationary while said chuck body and pinions are moved relative thereto, whereby said toothed ring and roller-jaw retaining ring are held stationary while said cam-ring is rotated relative thereto thus causing said cam-faces to force said roller-jaws against the work, and means for releasing the roller-jaws.

6. The combination with a pipe-working machine or the like having a positively rotated barrel, of a chuck comprising a main

- body portion secured to and adapted to rotate with said barrel, a cam-ring removably secured to and adapted to rotate with said body portion, a roller retaining ring 5 mounted within said cam-ring and adapted to move relative thereto, said roller retaining ring being provided with a plurality of transverse slots, a plurality of roller-jaw members mounted in said slots, cam-faces 10 on said cam-ring adapted to engage and control the movement of said jaws relative to the work, a toothed ring mounted around said roller retaining ring and secured thereto, a pinion mounted on said body portion 15 and in mesh with said toothed ring, a segmental rack mounted for sliding movement relative to said body portion, a second pin-
- ion mounted on said body portion and in mesh with said rack and said first named pinion, a spring-cushioned contact block 20 mounted in said rack, means adapted to engage said block to hold said rack stationary while said chuck body and pinions are moved relative thereto, whereby said toothed ring and roller-jaw retaining ring are held stationary while said cam-ring is rotated relative thereto thus causing said cam-faces to force said roller-jaws against the work, and means for releasing the roller-jaws. 25
- 30

In witness whereof, we have hereunto signed our names.

JOSEPH E. BAINES.
JACOB P. BOSLE.
